UNITED STATES PATENT OFFICE.

HENRY T. SPERRY, OF WATERBURY, CONNECTICUT, ASSIGNOR TO WATERBURY MFG.
CO., OF WATERBURY, CONNECTICUT, A CORPORATION.

PORABLE LAMP.

1,202,447.

Specification of Letters Patent. Patented Oct. 24, 1916.

Application filed April 23, 1915. Serial No. 23,276.

To all whom it may concern:

Be it known that I, HENRY T. SPERRY, a citizen of the United States, residing at Waterbury, in the county of New Haven 5 and State of Connecticut, have invented a new and useful Improvement in Portable Lamps; and I do hereby declare the following, when taken in connection with the accompanying drawings and the characters of 10 reference marked thereon, to be a full, clear, and exact description of the same, and which said drawings constitute part of this application, and represent, in—

Figure 1 a side view partly in section of 15 a portable lamp constructed in accordance with my invention. Fig. 2 a face view of the reflector with the locking nut in place. Fig. 3 a side view of the locking nut detached.

20 This invention relates to an improvement in portable lamps particularly such as are commonly known as cap or miners' lamps, and especially to acetylene gas lamps for this purpose. These lamps include a reflector; and the object of this invention is 25 to provide means for securely connecting a reflector with the lamp, and the invention consists in the construction hereinafter described and particularly recited in the 30 claim.

In carrying out my invention I employ an acetylene lamp comprising the usual water chamber 2 and carbide chamber 3 from which 35 gas passes to a burner tube 4 into which is inserted a usual lava tip 5, this tube projecting through one side of the water chamber 2. The usual reflector 6 is provided, surrounding the burner tube, and at the rear of the reflector is a collar 7 the inner end 40 of which is cut to fit the curvature of the water chamber 2 while the outer end has an opening. In the center of the reflector is an opening the edge of which is interlocked with the edge of the opening in the collar.

The opening in the reflector is larger than 45 the diameter of the gas tube 4, and the outer end of this tube is externally threaded to receive a nut 8 which has a flange 9, and the length of the nut is such that when screwed onto the tube 4 the flange will bear against 50 the reflector 6 so as to crowd the sleeve into close engagement with the water chamber 2 or case of the lamp. The outer end of this nut is formed with notches 10 by which it may be conveniently turned into place, and 55 the outer end of this nut projects beyond the burner tip 5 so as to not only form means for attaching the reflector to the lamp but also acts as a protector for the burner. Preferably and as shown the reflector will 60 be provided with a lighting device 11, and my invention is particularly desirable in lamps having such lighting means as the use of such lighting means imposes more or less strain upon the reflector. By thus connecting the reflector with the lamp, it is rigidly held in place and assembled with the greatest ease.

I claim:—

A portable lamp comprising a casing, a 70 gas tube projecting through one side of the casing, said tube threaded at its outer end, a burner tip within said tube, a reflector having a central opening in line with said burner, a collar connected to the rear of the 75 reflector and extending into contact with the casing, a nut extending through said opening and engaging with the outer end of said gas tube, said nut projecting outward beyond the said burner tip and formed with a 80 flange adapted to bear against the front face of the reflector whereby the reflector is firmly connected with the lamp.

HENRY T. SPERRY.
